UNITED STATES PATENT OFFICE.

ELLIS J. BOYD, OF OAK PARK, ILLINOIS.

COMBINATION HACK AND SCROLL SAW.

Application filed February 7, 1925. Serial No. 7,656.

This invention relates to combination hack and scroll saws, and has for one of its objects the provision of a device of this character wherein the blade may be readily secured in the plane of the frame or in any angular position with respect to said plane when it is desired to use the device as a hack saw.

A further object of the invention is the provision of a saw of the character stated wherein the blade may be readily released for free rotation when it is desired to use the device as a scroll saw.

A still further object of the invention is the provision of a saw of the character stated wherein the blade carrying clamps may be simultaneously and similarly rotated during the use of the device as a scroll saw in order to prevent the twisting of the blade.

With the above and other objects in view, the invention consists of the construction, combination and arrangement of parts hereinafter fully described and claimed, and illustrated in the accompanying drawing, wherein:

Figure 1 is a view in side elevation of a combination hack and scroll saw constructed in accordance with my invention, the housing for the shaft of the saw being in vertical section,

Figure 2 is a sectional view taken on the plane indicated by the line 2—2 of Figure 1,

Figure 3 is a detail sectional view taken on the planes indicated by the line 3—3 of Figure 1,

Figure 4 is a detail sectional view taken on the plane indicated by the line 4—4 of Figure 1, and

Figure 5 is a detail sectional view of one of the drums of the saw.

Corresponding and like parts are referred to in the following description, and designated in the accompanying drawing, by similar reference characters.

The saw comprises a U-shaped frame. 1 designates the cross bar and 2 and 3 the arms of the frame. Sleeves 4 and 5 are fixed to the outer ends of the arms 2 and 3, respectively. A drum 6 is located at and contacts with the outer end of the sleeve 4 and is rotatably supported by this sleeve through the medium of a journal 7 which is preferably formed integrally with the drum and which is threaded at its inner end for the reception of a lock nut 8 con-

tacting with the inner end of the sleeve. The drum 6 and its journal 7 are provided with a bore 9 of polygonal formation in cross section for the reception of the similarly formed shank 9^a of a saw clamp 10. The shank 9^a has a snug fit in the bore 9 to prevent any relative rotary movement between the drum 6 and clamp 10. The shank 9^a is provided with a threaded stem 11 upon which a handle 12 is mounted. To prevent the handle 12 from having any rotary movement with respect to the stem 11, a lock nut 13 is mounted upon the stem for contact with the inner end of the handle. A drum 14 is located at the outer end of the sleeve 5, it is rotatably supported by this sleeve, and it is provided at its inner end with a saw clamp 15. The saw clamps 10 and 15 may be of any well known or appropriate construction adapted to removably receive the ends of a blade 16. Brackets 17 are secured to the arms 2 and 3 and extend outwardly beyond the cross bar 1. Blocks 18 to which the end of a tube or housing 19 is secured, are adjustably carried by the brackets 17. Stems 20 carried by the blocks 18 pass through openings 21 in the outer ends of the brackets 17 for the reception of nuts 22 by means of which the blocks may be adjusted. A shaft 23 journaled in the housing 19 extends laterally beyond the brackets 17 and fixed upon its extended ends in alinement with the drums 6 and 14 are drums 24 and 25. A pair of cables 26 extend from the drum 6 to the drum 24 and are wound on these drums in opposite directions from their center towards their ends, the free ends of the cables being secured to the flanges of drums. A pair of cables 27 extend from the drum 14 to the drum 25 and are wound on these drums in opposite directions from their centers toward their ends and have their ends secured to the flanges of the drums.

The connection established between the drums 6 and 14 by means of the cables 26, drum 24, shaft 23, drum 25 and cables 27, is such that when the drum 6 is rotated by means of the handle 12 the drum 14 will be simultaneously and similarly rotated, and due thereto the blade 16 may be rotated without imparting any twisting strain thereto during the use of the device as a scroll saw. When it is desired to use the device as a hack saw, the lock nut 8 is turned up to secure the drum 6 against

rotation. This drum will in turn secure the drum 14 against rotation through the medium of the cables 26, shaft 23, and cables 27. The adjustability of the blocks 18 permit 5 the cables 26 and 27 to be maintained under such tension as to prevent any lost motion between the drums 6 and 14. The device is simple, durable and efficient, and it may be readily converted from a hack saw into a 10 scroll saw or from a scroll saw to a hack saw and this may be done by merely turning the lock nut 8 in a direction to either free the drum 6 or lock it to the sleeve 4.

While I have described the principle of 15 operation of the invention, together with the device which I now consider to be the best embodiment thereof, I desire to have it understood that the device shown is merely illustrative, and that such changes may be 20 made therein when desired as are within the scope of the invention as claimed.

What is claimed is:—

A saw comprising a frame having a cross bar and parallel arms, drums journaled on the outer ends of the arms, saw clamps fixed 25 to the drums, brackets secured to the arms adjacent the cross bar and extending outwardly beyond the cross bar, blocks, means adjustably securing the blocks to the brackets, a tube located between and secured to 30 the blocks, a shaft journaled in the tube and projecting therefrom outwardly beyond the arms, drums fixed to the ends of the shaft in alinement with the first named drums, and cables connecting the first named drums to 35 the second named drums, said blocks being used to raise or lower the tube thereby loosening or tightening the cables.

In testimony whereof I affix my signature.

ELLIS J. BOYD.
